(57) **CLAIM**

The ornamental design for an air fryer as shown and described.

DESCRIPTION

FIG. 1 is a perspective view of an air fryer of the present invention;

FIG. 2 is front view of the invention shown in FIG. 1;

FIG. 3 is rear view of the invention shown in FIG. 1;

FIG. 4 is a left-side view of the invention shown in FIG. 1;

FIG. 5 is a right-side view of the invention shown in FIG. 1;

FIG. 6 is a top view of the invention shown in FIG. 1; and,

FIG. 7 is a bottom view of the invention shown in FIG. 1.

The invention is an air fryer, as shown in FIGS. 1 through 7. Contour lines are included in the various views of FIGS. 1 through 7 to depict surface curvature, flatness and/or other shapes.

1 Claim, 7 Drawing Sheets
